HEAT EXCHANGE MEANS

Filed May 28, 1926

Fig. 1.

UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEAT-EXCHANGE MEANS

Application filed May 28, 1926. Serial No. 112,380.

My invention relates broadly to heat exchange means and particularly to heat exchange units having means for advancing a column of air therethrough.

5 A particular object of the invention is to provide devices of the kind described having improved means for directing a column of air.

One form of the invention is embodied in a heat exchange unit adjustably suspended from a steam pipe or the like, the device preferably comprising a radiator core through which air is advanced by a fan driven by an electric motor. Positioned upon one side of 15 the radiator core are a plurality of vanes by means of which the direction in which the air is advanced is controlled.

Many other objects and advantages of the construction herein shown and described will 20 be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding parts:

30 Fig. 1 is a front elevation of a heat exchange unit embodying the invention;

Fig. 2 is a side elevation of the improved heat exchange unit; and

35 Fig. 3 is a section taken on line 3—3 of Fig. 1.

Referring to the drawing wherein I have shown a preferred embodiment of the invention, the improved heat exchange unit is designated generally by the reference character 10 and preferably comprises a housing 11 formed from upper and lower manifold members 12 and 13, respectively. It will be noted that the manifold members 12 and 13 are substantially rectangular and that they 40 are connected to each other by side plates 14 so that they form a substantially box-like chamber together with the side plates. Formed in the manifold members 12 and 13 are U-shaped passages 15 and projecting into 45 the manifold members 12 and 13 are nipples

17 and 18, respectively, which communicate with the U-shaped passages 15. The nipple 17 is operatively connected to a steam pipe 21 by means comprising a pipe union 22, a nipple 23 and a T fitting 24. The pipe 55 nipple 18 is operatively connected to a drain or return pipe 26 by a pipe union 27, a nipple 28 and an elbow 29. The pipe nipples 17 and 18 are coaxially disposed so that the heating unit 10 may be angularly adjusted. 60

Mounted upon the manifold member 13 is a bracket 30 which supports an electric motor 31 adapted to drive a fan 32. Positioned in front of the fan 32 and secured to the manifold members 12 and 13 by bolts 33 is a radiator core 34 comprising upper and lower tanks 35 and 36, respectively, which communicate with the U-shaped passages 15. The tanks 35 and 36 communicate with each other through tubes 38 which are preferably 70 formed from relatively thin sheet metal. It will be noted that the tubes 38 are provided with a plurality of fins 39 which are also preferably formed from relatively thin sheet metal. 75

Projecting forwardly from the radiator core 34 are a plurality of side plates 42 and 43 to which a plurality of substantially U-shaped vanes 44 are pivotally mounted by means preferably comprising rivets 46 or the equivalent. It will be noted that the lowermost vane 44 is pivotally connected to the side plate 43 by a pin 48 which is rigidly secured to the vane and has a lever 49 rigidly secured to it at its outer end. Pivotally secured to the 85 vanes 46 are links 50 which are disposed between the vanes and side plates 42 and 43, the construction being such that if the lowermost vane 44 is angularly displaced around its pivotal axis the other vanes 44 are similarly displaced. Depending from the lever 49 are rods or cables 52 and 53 which are preferably provided with suitable rings or handles 55 at their lower ends. Obviously, the rods or cables 52 and 53 may be manipulated 90 to adjust the vanes 44 so that the air advanced through the radiator core 34 by the fan 32 may be given any desired angle with respect to the horizontal. 95

The operation of the above described ap- 100

paratus is substantially as follows: Steam or hot water is supplied to the heat exchange unit 11 by the pipe 21, the unit being drained by the pipe 26. The electric motor is connected to any suitable source (not shown) of electrical energy and advances a column of air through the radiator core, which air is heated by the fluid in the tubes 38. The heat exchange unit 11 may be angularly adjusted around the coincident axes of the nipples 17 and 18 so that the fan will advance the column of air in any desired radial direction with respect to the axes of the nipples. The vanes 44 may then be adjusted to direct the air with respect to the horizontal.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. Heat exchange apparatus comprising a housing, tubular means for suspending said housing from a pipe, a radiator core carried by the housing and communicating with said pipe through said tubular means, means carried by the housing for advancing a column of air through said radiator core, and a plurality of adjustable vanes mounted on the housing for directing the current of air advanced through the radiator core.

2. Heat exchange apparatus comprising a housing, a radiator core, tubular means for suspending said housing and said core from a pipe, said core communicating with said pipe through said tubular means, means mounted within the housing for advancing a column of air through the radiator core, and means positioned in front of the core for directing the current of air advanced through said core.

3. Heat exchange apparatus comprising a housing, a radiator core, tubular means including a pipe union for suspending said housing and said core from a pipe, said core communicating with said pipe through said tubular means, means mounted within the housing for advancing a column of air through the radiator core, and means positioned in front of the core for directing the current of air advanced through said core.

4. Heat exchange apparatus comprising a housing, means for supporting said housing so as to permit rotation thereof, a radiator core carried by the housing, means carried by the housing for advancing a column of air through said radiator core, and a plurality of vanes mounted in front of the core for directing the current of air advanced through the radiator core, said vanes being movable

on axes perpendicular to the axis of rotation of said housing.

5. In a device of the kind described, the combination of a radiator core, members respectively provided for connection with a heating fluid supply and return, said members being respectively located at opposite ends of the radiator and said radiator and members being separately secured together, plates arranged upon opposite sides of said radiator core and being separately connected with said members, said members and plates being extended sidewise beyond the radiator core and providing an open ended box-like structure, an arm extending inwardly of the plates and members and providing a support, air advancing means secured to said arm, an element of said air advancing means being located in said box-like structure, and means for directing the current of air advanced through the radiator.

6. In a device of the kind described, the combination of a radiator core, members respectively provided for connection with a heating fluid supply and return, said members being respectively located at opposite ends of the radiator and communicating therewith, said radiator core and members being separably secured together, plates arranged upon opposite sides of said radiator and being separably connected with the ends of said members, said members and plates being extended beyond the radiator core and providing an open ended box-like structure, an arm arranged at one side of said radiator extending inwardly of the plates and members and providing a support, air advancing means supported by said arm, an element of said air advancing means being located between the radiator and the termination of the open end of said box-like structure, and means connected with said plates and arranged upon the opposite side of the radiator for directing the current of air advanced through the radiator.

7. In a device of the kind described, the combination of a radiator, members respectively provided for connection with a fluid supply and return, said members being respectively located at opposite ends of the radiator, plates arranged upon opposite sides of said radiator and connected with said members, said members and plates being extended endwise beyond the radiator and forming an open ended box-like structure closed at one end by said radiator, an arm extending inwardly of the plates and members into the open end of said box-like structure and providing a support, air advancing means secured to said arm, said air advancing means including a rotatable element located in the open end of said box-like structure, and pivoted means for directing the current of air advanced through the radiator.

8. In a device of the class described, the

combination of a radiator, members respectively provided for connection with a heating fluid supply and return and being arranged at the opposite ends and transversely to the tubes of said radiator, frame elements arranged at the opposite sides of the radiator and connected to the first mentioned members, said radiator providing a closure for one end of the frame, an arm extending inwardly of said frame and located at the open end of said frame, air advancing means secured to said arm for advancing air through the radiator, said air advancing means including a fan arranged at one side 10 of the radiator and within said frame, and means pivotally secured to said frame for directing the current of air advanced through the radiator.

9. In a device of the class described, the combination of members respectively provided for connection with a heating fluid supply and return, elements arranged at the opposite ends of said members, said members and elements being connected together 25 to provide a supporting frame, a radiator located in said frame and communicating with said members, an arm extending inwardly of said frame, air advancing means secured to said arm for advancing air 30 through the radiator, and means connected with said frame for directing the current of air advanced through the radiator.

10. In a device of the class described, the combination of a radiator including tubes 25 and transversely arranged fins, members arranged at the sides and ends of said radiator, said members providing walls of a housing for the radiator, an arm extending inwardly of said housing, air advancing means secured to said arm and located in said housing 40 for advancing air through the radiator, and pivoted means for directing the current of air advanced through the radiator.

In testimony whereof, I have hereunto
45 signed my name.

ARTHUR B. MODINE.
